SUBMERSIBLE AIRCRAFT

Antone Arruda, 12209 S. Eucalyptus Ave.,
Hawthorne, Calif. 90250

Filed Jan. 17, 1972, Ser. No. 218,637

Term of patent 14 years

Int. Cl. D12—07

U.S. Cl. D71—1 G

FIG. 1

FIG. 2

FIG. 3

FIG. 4

FIG. 5

FIG. 1 is a fragmentary top plan view of a submersible aircraft showing my new design, it being understood that the aircraft is symmetrical about a longitudinal centerline;

FIG. 2 is a front elevation view thereof;

FIG. 3 is a side elevation view thereof;

FIG. 4 is a fragmentary perspective view of the bottom rear portion thereof;

FIG. 5 is a top perspective view of the submersible aircraft.

I claim:

The ornamental design for a submersible aircraft, as shown and described.
